UNITED STATES PATENT OFFICE

2,088,232

LAUNDRY BAG

John Stewart Cumming, Pawtucket, R. I., assignor to Colonial Laundries, Inc., a corporation of Rhode Island

Application January 9, 1936, Serial No. 58,271

3 Claims. (Cl. 229—62)

This invention relates to bags or receptacles, and more particularly to a laundry bag, and has for one of its objects to provide a novel construction of laundry bag composed of paper in which the bottom thereof temporarily holds the bag in a folded condition to permit its use as an advertising circular.

Another object of this invention is to provide a paper bag construction for laundry purposes in which the open top end of the bag is temporarily confined and held in a folded relationship with respect to and by means of the bottom of the bag structure.

Another object of this invention is to provide a paper laundry bag construction having an open top end portion and a binding or closure member mounted adjacent to the outer end of said top portion which will form a binding around the gathered folds of the top end of said bag of sufficient diameter to retain the bag contents against escape therefrom and in closed form for transit to the laundry.

Another object of the invention is the provision of a paper bag for holding laundry wherein the binding or closure device therefor will maintain the capacity of bag fixed and constant irrespective of the weight or amount of its contents thereof.

Another object of this invention is to provide a paper laundry bag whereby its contents may be limited and for which a fixed service charge may be assigned therefor without the necessity of actually weighing or counting the goods to determine the cost thereof.

With these and other objects in view, the invention consists of certain novel features of construction as will be more fully described and particularly pointed out in the appended claims.

In the accompanying drawing:

Fig. 1 is a perspective view showing one embodiment of the invention;

Fig. 2 is a perspective view of the bag at next to the final step of production with the top end folded in position to be temporarily confined beneath the flap;

Fig. 3 is a like view at the final step of production with the bag in completed form for distribution;

Fig. 4 is a perspective view of the bag showing closure means for temporarily binding the top end thereof for transit to the laundry; and

Fig. 5 is a fragmentary view of the top end portion of the bag showing another closure means for temporarily binding the bag end.

When articles requiring laundering are put up for the laundry, they are usually thrown indiscriminately into a box or a bag of different and varying sizes. The result has been that the various pieces become jumbled into a confused and not readily separable mass so that, when

the wash arrives at the laundry, it is necessary to sort and classify the various pieces and put them into segregated groups. Since it is the customary practice for the laundry to charge for their work either by the pound or by the piece, it becomes further necessary for them, in addition, to weigh or count the number of pieces sent in each wash to determine the proper charge which is to be made for their work. In the past, various types of containers have been proposed in an attempt to overcome the foregoing defects and disadvantages, but they have not been entirely satisfactory in practice. It is, therefore, desirable to provide a laundry bag or receptacle which is made of a relatively inexpensive material whereby it may be thrown away after use. It is also desirable to provide a laundry bag in a size which will serve as measure for the cost of the package and in a form so that it may serve both as a container for the laundry and as an advertising medium, and which can be made for substantially the same cost as an ordinary advertising circular yet when distributed to a prospective customer will not be quickly thrown away unopened, but will instead, by its unique construction, attract attention to the advertising which it carries, and in addition, provide a useful container which will be kept around and used, if desired, for the sending of a trial wash; and in order that these features may be accomplished, I have provided a bag construction having generally rectangular front and back walls which are flattened down and folded so that the closed bottom of the bag is arranged upon the open top end portion thereof in which the latter is maintained in a folded position by the overlapping portion of the bag bottom which forms a flap temporarily confining said folded top portion of the bag and fastened thereto by an adhesive body; and I have also provided a closure member adjacent to the open end portion of the bag and which prior to use will lie beneath the overlapping flap of the folded bag bottom but will be immediately available for use, upon the tearing of the adhesive body and raising of the flap, and so can be wound around the neck of the bag to secure the same and prevent escape of its contents when the bag is filled with laundry articles; and the following is a more detailed description of the present embodiment of this invention, illustrating the preferred means by which these advantageous results may be accomplished:

With reference to the drawing, 10 designates the body of the bag, and as shown in Figure 4 of the drawing, it comprises front and back walls 12 and 13, respectively, and is provided with an open top end portion 14 and a closed bottom 15. The bag consists of inexpensive sheet material, preferably strong paper, which has been cut to the proper shape and dimensions to form

a bag of the size desired, and the outer flaps thereof are pasted to the body to produce the completed container.

In order that the bag may serve the dual purpose as a laundry receptacle and as an advertising vehicle to display printed matter for soliciting new customers for the laundry, the bag is made in the form of a folded package, in which the bottom 15 is folded about a line 16 transversely 5 of its middle and passing through the end corner points 17 and 18, respectively, to form an inwardly projecting cover flap 19 which extends downwardly over the top end portion 20 of the bag to temporarily confine and hold said portion 10 after it has been folded widthwise on the transverse line 21, as shown in dotted outline in Figure 4 of the drawing. The bag is scored along the line 21 at the time of its formation to definitely locate the point of fold. The flap 18 may be cemented or otherwise secured in place on the top portion 20. In the preferred construction, a 15 gummed sticker or seal 22 is pasted to the flap 19 and the top bag portion 20 at the overlapping portions thereof. This sticker may also serve to 20 fasten to the flap 19 a request post-card 23, by means of which notice is sent to the laundry that they are to call for the wash. The walls 12 and 13 may display advertising matter, such as the 25 name and trade-mark of the laundry and descriptive printed matter highly informative of the type of service rendered.

As illustrated in Figures 1, 2 and 4 of the drawing, a binding or closure member is mounted on the top portion 20 of the bag and at a predetermined position thereon adjacent to its open end 14 so as to maintain the capacity of the bag constant at a fixed point of closure irrespective of the weight or number of pieces of goods put therein, and in the specific construction illustrated this preferably comprises a gummed closure strip 25 which is secured at its inner end 26 to the wall 12 of the bag, the outer end 27 of the strip 25 being loose whereby it may be free to be wound around the neck of the bag, as shown in Figure 1, and sealed by pasting over its inner fixed end 26 or cemented to the outside of the bag so as to retain the bag in a closed position and to prevent escape of its contents.

A modification of the invention is illustrated 50 in Figure 5 of the drawing in which the closure member comprises a tie fastener 30 having a pair of loose strings 31 and 32, the inner ends of which are secured to an eyelet 33 suitably fastened in the wall 13 of the bag portion 20, the 55 strings 31 and 32 being wound about the neck of the bag and then wound around the eyelet 33 and prevented from slipping sidewise therefrom by a washer 35.

By this arrangement a bag construction is provided which may serve as a container for pieces of flatwork and wearing apparel to be laundered and also as an advertising display package. Furthermore, since the position of the closure is fixed, the capacity of the bag is made constant and hence the charge for the service, based on its 65 fixed contents, may be thus determined in advance for the particular size of bag which is to be filled. It is to be understood that the bag must be closed by the means provided in order 70 that the fixed charge will apply.

The foregoing description is directed solely to-

wards the construction illustrated, but I desire it to be understood that I reserve the privilege of resorting to all the mechanical changes to which the device is susceptible, the invention being defined and limited only by the terms of the 5 appended claims.

I claim:

1. A laundry bag comprising a foldable body of paper having a closed bottom, front and back walls, and an open top end portion, the upper 10 portion of said bag body being folded and doubled upon itself and temporarily confined at its top edge by and beneath a fold of the bottom of the bag, said folded bag bottom extended around and over the top end of the upper portion of said 15 bag to form a flap extending lengthwise along said portion, means for retaining said bottom flap in a folded position above the upper portion of said bag, and closure means for said bag secured to said upper portion of the bag adjacent 20 to the open edge thereof and normally disposed beneath said folded bottom flap when not in use but applicable about the neck of the bag when the latter is filled.

2. A laundry bag comprising a foldable body of paper having a closed bottom, front and back walls, and an open top end, the upper portion of said bag body being folded and doubled upon itself and temporarily confined at its top edge by and beneath a fold of the bottom of the bag, 30 said folded bag bottom extending around and over the top end of the upper portion of said bag to form a flap extending lengthwise along said portion, means for retaining said bottom flap in a folded position above the upper portion of said 35 bag, and closure means for said bag secured to a wall of said upper portion of the bag adjacent to the open end thereof and normally disposed beneath said folded bottom flap when not in use but applicable about the neck of the bag when 40 the latter is filled, said closure means comprising a laterally extending adhesive closure strip of shorter length than the width of said folded bag and having one end fixedly secured to said bag wall at a predetermined position thereon 45 with the other end loose and connectible with said fixed end when the strip is wound about the bag neck and thus serve to determine the quantity of fillable space of said bag when the latter is unfolded for receiving pieces of laundry and 50 thereby provide a fixed level of closure of the same representing a substantially constant measure of goods corresponding to a unit of price.

3. A laundry bag comprising a foldable body of paper having a closed bottom, front and back 55 walls, and an open top end portion, the upper portion of said bag body being folded and doubled upon itself and temporarily confined at its top edge by and beneath a fold of the bottom of the bag, said folded bag bottom extending around 60 and over the top end of the upper portion of said bag to form a flap extending lengthwise along said portion, and closure means for said bag secured to said upper portion of the bag adjacent to and along the open edge thereof and normally disposed beneath and concealed by said folded bottom flap when not in use but applicable about the neck of the bag when the latter is filled.

JOHN STEWART CUMMING. 70
